HOLDING DEVICE

Adolph Jensen, New York, N. Y.

Application March 23, 1943, Serial No. 480,144

3 Claims. (Cl. 24—3)

This invention relates to holding devices suitable to hold pencils and is herein illustrated in the form of a clip device carried on and cooperating with the stiff body of a helmet so that a pencil may be held securely gripped between the clip and the helmet body.

Ship workers, iron erectors and carpenters who wore heavy smooth protective helmets, have hitherto deemed it impossible to take hold of a pencil or crayon readily, especially when wearing gloves. Such men, especially when doing outdoor work have carried a pencil in a pocket, usually a pocket inside a coat, with the result that the typical worker, who unexpectedly needed a pencil, first removed a glove, unbuttoned his coat, felt for the pencil, and, having found it, pulled it out, buttoned his coat, put on his glove (at least if an iron erector), and then proceeded to make the desired mark. When the mark or marks were made, the process was reversed to put the pencil back, and go to work again after replacing the glove a second time.

In a large shipyard, for example, this series of wasted motions takes place several thousand times a day, thus wasting hundreds, if not thousands of man-hours each day.

According to the present invention the workman may be able to quickly seize his pencil from his protective helmet, even wearing his gloves, and after using the pencil, quickly and securely replace it on the helmet in a small fraction of the time now wasted.

In the form disclosed in some detail the stiff body of a helmet is perforated to receive a screw body which is adapted to press against the helmet a spring blade, with the result that the blade serves to hold the pencil by gripping it between the blade and the helmet surface.

Other features and advantages will hereinafter appear.

In the accompanying drawing:

Fig. 1 is a side view of a helmet showing a clip holding the pencil in place;

Fig. 2 is a sectional view on the line 2—2 of Fig. 1;

Fig. 3 is a face view of the clip and some parts seen from the helmet side; and

Fig. 4 is a face view seen from the other side.

In the form shown a rigid workman's helmet 10 made of fibre-reinforced synthetic plastic to make a resilient structure is perforated at 11 about level with the top of the usual suspended sweat-band support, and a headed screw 12 is passed through the perforation so that the broad flat head 13 lies against the inner surface of the

helmet, and the screw body 14 projects, say, one-half inch outside the helmet.

Then a spring clip 15 perforated at 16 and carrying a dished spacer 17 is slipped over the screw body 14 so that its arched body 18 stands free of the helmet surface while its downturned bend 19 lies against the helmet at a point 20 where the helmet is turning well inwards. From the bend 20, above the bend 19, the end of the clip 15 bends slightly away from the helmet, or standing vertical, so that a pencil is readily caught by the free end 21.

In fact, a workman, holding his pencil between his thickly gloved fingers, finds it easy to slip his pencil down the smooth hard surface of the helmet and catch the pencil behind the end 21 by feeling, despite the awkwardness caused by the thick glove.

The clip 15 may have about the resiliency of 20 corset steels and extends below the spacer 17, bending toward the helmet 10 at 22.

The dished spacer 17 is shown in the form of a flat annular rim 23 lying upon the surface of the helmet 10 and a dished body 24 larger in 25 diameter than the half-inch side clip 15, and slotted at 25, 26 to receive the clip 15 at its upper and lower parts (as seen in Figs. 2 to 4), so that it firmly holds the clip against turning, because the clip enters beneath the surface of the 30 dished body 24 at the slot 25 and comes out at 26.

The clip 15 is held to the spacer 17 by being 35 upset at 27 or riveted where it is perforated at 16 to permit the screw 14 to pass, the spacer being correspondingly perforated, so that the edges of the clip around the perforation 16 overlie the edges of the spacer 17 as best shown at 27 in Fig. 2.

When the clip 15 lies upon the surface of the 40 helmet 10 and the screw 14 is in position in the perforations 11 and 16, the clip 15 is readily locked in place by screwing down a wing-nut 28 on the screw and tightening it against the spacer 17 or the upset edge 27. For convenience in releasing the screw head 13 may be slotted at 29.

A stationary total length of clip from the perforation 16 to the end 21 about 2½ inches, and the whole device or any part may be made of galvanized or rust-proof or stainless steel.

Having thus described one form of the invention in considerable detail, what is claimed is:

1. The combination of a resilient clip adapted to bear against the hard surface of a head piece, a spacing member through which the clip is passed, and a screw device having a head behind

the surface and passing through the clip and spacing member to hold the clip to the outer surface.

2. The combination of a resilient clip adapted to bear against the surface of a hard helmet, a spacing member having a rim which bears against the helmet, and a dished portion having slots through which the clip passes, a headed screw adapted to bear against the interior of the helmet and passing through perforations in the helmet and spacing member and clip, and a nut screwed down on the screw against the spac-

ing member and clip to hold them to the helmet.

3. A pencil clip including a resilient strip having an outturned end, a dished member having slots through which the strip passes, a headed screw passing through perforations in strip and dished member, up set margins on the strip perforations overlying the edges of the dished member perforation to hold the strip to the member, and a nut screwed down on the screw to draw the head of the screw against the interior of the helmet.

ADOLPH JENSEN.
